MEANS FOR REMOVABLY MOUNTING
FLOOR RACKSStacy B. Haseltine, La Grange, Ill., assignor to
W. H. Miner, Inc., Chicago, Ill., a corporation
of Delaware

Application July 23, 1938, Serial No. 220,934

18 Claims. (Cl. 16—174)

This invention relates to improvements in means for removably mounting floor racks of refrigerator cars.

One object of the invention is to provide a removable floor rack construction for railway cars of the refrigerator type, hinged to the car in such a manner that the sections thereof may be swung upwardly out of the way to substantially vertical position, the hinge members of each rack section, which provide for the swinging movement, being so designed and arranged that they become readily detachable from the car upon the rack being swung to a predetermined position.

A more specific object of the invention is to provide hinge members of the character set forth in the preceding paragraph, which are pivotally connected to the hinge socket elements mounted on the car, wherein the socket elements are provided with retaining means and the pivots of the hinge members are designed and arranged to slide lengthwise of said sockets during swinging movements of the rack sections to assume a position beyond the limits of the retaining means to render said hinge members readily detachable from the socket elements.

A further object of the invention is to provide a detachable hinge member having a hinge pin swingingly connected to a keeper element, provided with a guideway within which the pivot is both rotatably and slidably accommodated, wherein the hinge member is provided with means for closing the guideway to seal the same against entrance of dirt and other foreign material when the hinge member is swung to a predetermined position.

A still further object of the invention is to provide a removable floor rack construction hinged to the floor of the car by pivot means on the rack, detachably connected to a socket element mounted in the floor of the car, wherein the rack carries means for effectively closing the socket to exclude dirt and other foreign material when the rack is either in flat position overlying the floor or in raised vertical position against the wall of the car.

Other objects of the invention will more clearly appear from the description and claims hereinafter following.

In the drawings forming a part of this specification, Figure 1 is a vertical sectional view through a portion of a floor rack section, corresponding to the line 1—1 of Figure 3, also showing the inner face of a portion of the side wall of a refrigerator car, and illustrating my improvements in connection therewith. Figure 2 is a top

plan view of the floor rack section shown in Figure 1, partly broken away, showing the side wall of the car in horizontal section, illustrating the improvements shown in Figure 1. Figure 3 is a vertical sectional view, corresponding substantially to the line 3—3 of Figure 1. Figure 4 is a view, similar to Figure 3, but showing the rack section swung upwardly to vertical position against the side wall of the car. Figure 5 is a vertical sectional view in a plane parallel to the side wall of the car and extending through a portion of a floor rack section and the floor of the car, illustrating another embodiment of the invention, said section being taken substantially on the line 5—5 of Figure 6. Figure 6 is a vertical sectional view, corresponding substantially to the line 6—6 of Figure 5. Figure 7 is a horizontal sectional view, corresponding substantially to the line 7—7 of Figure 6. Figure 8 is a view similar to Figure 6, but showing the parts in a different position, the rack being illustrated as swung partly upwardly. Figure 9 is a view similar to Figure 6, but showing the rack section swung upwardly to vertical position against the side wall of the car.

In said drawings, 10 indicates a portion of one of the side walls of a refrigerator car, and 11 the adjacent portion of the floor thereof. One of the sections of the floor rack is indicated by 12, a portion only of said section being shown. The floor rack section 12 is of a type commonly employed in refrigerator cars. As is well known to those skilled in this art, the floor rack of a refrigerator car is composed of a plurality of similar sections like the section 12, these sections being arranged in sets at opposite sides of the center line of the car and covering the entire floor area which is available for lading. The sections at opposite sides of the center line of the car are usually arranged to be swung to vertical position against the corresponding side wall so as to clear the floor and make the same accessible. When the car is used for lading requiring elevation above the floor, the floor rack sections are disposed in horizontal flat position overlying the floor and, as hereinbefore stated, cover the entire floor space available for lading. It is a common practice to remove the floor rack structure from the car to render the car available for lading which does not require elevation above the floor of the same, and for this purpose the individual sections are made removable as shown in Olander Patent No. 2,106,852, February 1, 1938. The structure of the rack section 12 in connection with which my improvements are disclosed is

substantially the same as that of any one of the individual sections disclosed in the Olander patent. The section 12 comprises transverse, spaced slats secured to laterally spaced, supporting beams or stringers extending lengthwise of the car. These slats are indicated by 13-13. One only of the stringers of the rack section is shown in the drawings and the same is indicated by 14. Each section 12 forms a unit which is bodily removable from the car.

Referring first to the embodiment of the invention illustrated in Figures 1 to 4 inclusive, the floor rack section 12 is connected to the floor 11 of the car by my improved hinged means, indicated by A. A number of such hinge means pivotally support the rack section 12 at a plurality of points along the outer edge of the rack section and adjacent the corresponding side wall of the car.

20 My improved hinge means A comprises broadly a hinge member B fixed to the rack; a hinge socket or keeper member C fixed to and seated in the floor of the car; and a pivot member D formed rigid with the member B and engaged 25 with the member C.

The hinge member B comprises a pair of substantially flat webs 15 and 16 at right angles to each other, and a pair of arms 17 and 18 respectively parallel to the webs 15 and 16 and 30 at right angles to each other. The webs 15 and 16 preferably correspond in width to the width of one of the slats 13 of the rack section 12. The hinge member B is fitted to the section 12, with the web 15 underlying the projecting portion of 35 one of the slats 13 and the web 16 abutting the vertical outer face of the outermost stringer 14 of said rack section, and is secured by bolts 116-116-116, extending through said webs 15 and 16 and the slat 13 and stringer 14, respectively.

40 The arms 17 and 18 are of lesser width than the webs 15 and 16, and the arm 17 is reenforced by a longitudinally extending central rib 19 on the outer side thereof. At the corner junction of the arms 17 and 18, the hinge member B is provided with an enlarged projecting portion inclined with respect to both of said arms. This projecting portion carries the hinge pin D, which is formed integral therewith, and projects from opposite sides of said portion in the manner of 45 trunnion means and forms therewith a T-head. As will be seen upon reference to the drawings, the hinge pin D is parallel to the stringer 14 and 50 outwardly offset with respect to both arms.

The arm 17 is laterally enlarged at its outer 55 end, said enlarged portion projecting from opposite sides of the arm, thus forming a T-headed end portion 20. The narrower remaining portion of the arm 17 and the entire arm 18 are made of the same width for a purpose herein- 60 after pointed out. As shown most clearly in Figures 3 and 4, the arm 17 extends beyond the web 16, and said extending portion underlies the stringer 14, abuts the bottom face thereof and projects beyond said stringer, the T-headed section 65 thereof being located beyond said stringer. The arm 18 projects a short distance beyond the web 15, engages the outer end edge of the slat 13, as shown in Figure 3, and terminates below the top of said slat.

70 The hinge socket or keeper member C, which is preferably in the form of a casting, is seated or completely sunk into a pocket 121 provided in the floor 11 of the car. The socket member C includes a substantially rectangular, horizontally disposed, flat plate 21, which is counter-

sunk into the floor 11 so that the top surface of said plate is flush with the top surface of the floor. The plate 21 forms the top wall of the socket member C. The socket member C has spaced side walls 22-22, end walls 23 and 24, 5 and a bottom wall 25 spaced from said top wall. The end wall 23 is preferably rounded, as shown in Figure 4, and the end wall 24 is inclined upwardly and forms a continuation of the bottom wall 25. As further shown in Figures 3 and 4, 10 the pocket 121 is continued for a short distance beneath the side wall 10 of the car and the pocket portion of the casting C, which snugly fits the pocket 121, partially underlies said side wall. The platelike top wall, which is counter- 15 sunk into the floor, protrudes beyond the side walls 22-22 of the casting C and thereby provides securing flanges by which the casting is fixed to the floor. Screws extending through the plate 21 and into the floor are preferably em- 20 ployed for rigidly fixing the socket casting to the floor. The plate 21 is longitudinally slotted, as indicated at 26, said slot being transversely enlarged at the end thereof remote from the wall 10 of the car, as indicated at 27. The enlarged 25 portion 27 of the slot is of such a shape and width as to freely admit the pivot pin member D of the hinge member B, and the width of the slot 26 is such that the arms 17 and 18 fit the same to close said slot against admission of foreign material. As will be evident, the slot 26 is of generally T-shaped formation and the narrower portion thereof provides, in effect, side ledges or retaining walls which overhang the 30 guideway 28 at a point between the side walls 35 22-22 of the socket member C, which ledges or retaining walls prevent disengagement of the pivot pin D from said guideway when said pin is located between said ledges. As will be evident the enlarged portion 27 of the T-shaped 40 slot is provided by cutting away the retaining walls. The end of the slot 26 remote from the enlarged portion 27 thereof terminates flush with the inner surface of the side wall 10 of the car, as clearly shown in Figures 3 and 4. As shown 45 in Figures 3 and 4, the hinge pin D of the member B is engaged in the guideway 28 and pivotally supports the floor rack section 12 in such a manner that it is reliably anchored to the car while being swung from horizontal to vertical 50 position, and vice versa. When in the position shown in Figure 3, with the rack 12 horizontally overlying the floor, the arm 17 of the member B is seated in the slot 26 of the socket casting C, effectively closing the same, the enlarged T- 55 headed portion 20 of said arm snugly fitting the enlarged T-portion 27 of said slot to seal the same. When the rack is swung to vertical position against the side wall of the car, as shown in Figure 4, the arm 18 and the pivot pin D close 60 the slot 26 and its T-shaped portion 27. The socket member C is thus protected from accidental entrance of dirt and other foreign matter, which might otherwise interfere with the proper operation of the hinge means. In this connection it is pointed out that the hinge member B when in the position shown in Figure 3 is effectively held against lengthwise movement with respect to the socket member C by shouldered engagement of the T-headed end of the arm 17 65 with the end wall of the enlarged portion of the slot 26.

When the section 12 has been anchored to the car, the hinged arrangement thereof allows the same to be swung upwardly out of the way 70 75

against the side wall of the car in the usual manner, and, as is common practice, to be supported in said out of the way position by suitable holding or latching means. As the rack section 5 is swung from the horizontal position shown in Figure 3 toward the vertical position shown in Figure 4, it swings on the hinge pin D while the arm 18 of the hinge member B rides downwardly on the side wall of the car, thereby forcing the hinge 10 pin to travel from one end to the other of the guideway, while rotating, until it finally reaches the position shown in Figure 4 and comes into alignment with the enlarged portion 27 of the slot 26. The arm 18 thus forms in effect a lever 15 member which rides on the side wall of the car to control said sliding movement of the pivot. As will be evident when the parts reach the last named position, the rack section may be readily detached from the car by merely raising the same 20 so as to disengage the hinge pin D from the socket member C, the pin passing freely upwardly through the enlarged opening 27 of the slot 26.

When it is desired to convert the car for service for lading which does not require elevation from 25 the floor, the various rack sections 12 are detached in the manner described and completely removed from the car, thereby making available the maximum lading capacity of said car. It is further obvious that when the rack sections are 30 in horizontal position, overlying the floor, they must be first swung to vertical position before detachment and removal of the same can be effected.

To replace the rack sections in the car, each 35 section is placed in vertical position against the corresponding side wall of the car and the hinge pin engaged within the socket C by passing the pin through the enlarged opening 27 of the slot 26 into the guideway 28 as illustrated in Figure 4. The rack sections are thus made ready for use 40 and are securely anchored to the car for swinging movement and into overlying relation with the floor.

Referring next to the embodiment of the invention illustrated in Figures 5 to 9 inclusive, the 45 floor rack section 12 is connected to the side wall 10 of the car by the improved hinge means E, several of which are employed in connection with each rack section in the same manner as the 50 hinge means A, hereinbefore described.

My improved hinge means E comprises broadly a hinge member F fixed to the rack; a hinge socket or keeper member G fixed to the side wall of the car; and a pivot element H formed rigid 55 with the member F and engaged with the socket member G.

The hinge member F comprises a bracket portion 60 30, fixed to the floor rack section 12, and an outwardly extending, right angular arm 31 on 65 said bracket portion having the relatively heavy angular end section thereof upstanding with respect to the rack section and provided with laterally projecting trunnions above the level of the rack which form the pivot pin element H or 70 pivot of the hinge means E. As clearly shown, the pivot pin portion of the angular section of the arm 31 is in the form of a T-head. The bracket portion 30 of the hinge member F has a substantially flat platelike web portion 32 by 75 which the bracket is secured to the outer face of the stringer 14 which is nearest the outer edge of the rack section, the web bearing on the stringer and being fixed thereto by bolts 33—33 or other securing elements extending through said 80 web and the stringer.

The inner section of the arm 31 includes a flat platelike portion or web 34 having an upstanding central rib 35, said platelike portion being disposed at right angles to the web 32 and continuous therewith. The arm 31 is preferably reinforced by laterally projecting ribs 36—36 along its edges. As shown most clearly in Figure 5, the rib 35 of the platelike portion 34 is seated between two adjacent slats 13—13 of the rack 12, and the platelike portion 34 at opposite sides of said rib 35 underlies these slats and is secured thereto by bolts or other fastening elements, also indicated by 33, extending through said platelike portion and the slats 13—13.

The hinge socket or keeper member G, which 15 is preferably in the form of a casting, is seated in or completely sunk into a pocket 37 of substantially circular outline provided in the face of the vertical side wall 10 of the car. The socket member G includes a substantially circular, vertically disposed, flat plate 38 and a boxlike chamber 39 of substantially rectangular outline, formed on the rear side of said plate, the boxlike portion being of smaller size than the plate so that the latter projects laterally beyond the former on all sides thereof. At opposite sides of the boxlike portion, the plate 38 has inset portions 40—40, the back walls of which are in the same plane as the back wall of the boxlike portion 39. The socket member is secured in place by any 20 suitable securing elements, preferably bolts, which extend through the back walls of the inset portions 40—40, the nuts of the bolts being accommodated in the recesses formed by said insets. The plate 38 forms the front wall of the 25 boxlike portion 39 and is provided with a vertical slot 41 disposed centrally between the vertical side walls of the portion 39 and of the same length as the vertical interior dimension of said boxlike portion. The slot 41 is laterally enlarged or widened near its lower end, by cutting away the metal of the plate 38 at opposite sides of the slot 41 as indicated at 42—42, thereby 30 providing an opening of substantially cross shape. The widened portion 42—42 corresponds in width 35 to the interior width of the boxlike portion 39, said opening being of such a size as to permit the pivot pin element H to pass freely therethrough. The front plate of the socket member G, at opposite sides of the slot 41, provides 40 retaining ledges or walls for the pivot pin H, and the space between said plate 38 and the back wall of the boxlike portion 39 provides a guideway 43 for the pivot pin H and accommodates 45 the same for both rotary and sliding movement. 50

As will be evident, the hinge member F may be 55 readily assembled with the hinge socket member G or withdrawn therefrom, when the rack section is properly tilted, the pivot pin element H being passed through the enlarged portion 42—42 60 of the slot 41. This tilted position of the rack is shown in Figure 8. In order to disengage the hinge member F when in the position shown in this figure, the rack is pulled laterally away from the wall 10 of the car, the pivot pin H passing freely through the enlarged portion of the slot 41. To engage the hinge member with the socket, the hinge pin is aligned with the enlarged portion 65 of the slot by angularly tilting the rack section, as shown in Figure 8, and the rack section 70 pushed toward the wall 10, thus entering the hinge pin through said enlarged portion of the slot. The rack section may then be dropped to the position shown in Figure 6, thereby bringing the pivot pin H in back of the overhanging ledges 75

of the platelike portion 38 of the socket member G and effectively anchoring the hinge member to the socket. It is further pointed out that during swinging movement of the rack section the 5 pivot of the hinge member is forced to slide lengthwise in the guideway 43 due to the fact that the outer end section of the arm 31 of the hinge member F forms a lever which rides on the floor of the car while the rack is being swung 10 toward and away from the side wall of the car.

As shown in Figure 6, the floor rack section 12 is supported by the hinge means E in such a manner that it is reliably anchored to the car wall for swinging movement, either from horizontal to vertical position or from vertical to horizontal position, the pivot pin H being guided to slide lengthwise of the guideway of the socket G while having rotary movement on its axis, the hinge member F being removable only when in the position shown in Figure 8. As will be further evident upon reference to this figure, the arm 31 of the bracket 30 is formed of such a contour that it is supported for outward and inward sliding movement toward and away from the wall 20 on a substantially flat, straight, bearing surface 44 on the lower edge thereof, thus facilitating attachment and removal of the hinge member. The edge portion of the arm 31 beyond the flat bearing surface 44 is curved, as indicated 25 at 45, to provide a guide on which the arm slidingly rocks while the rack is being raised from the position shown in Figure 8 toward the position shown in Figure 9, and lowered to the position shown in Figure 8. The rolling rocking action thus provided effectively holds the pivot pin H in the guideway of the socket member G, as the pin passes the enlarged portion of the slot 30 35 41 during upward and downward swinging movement of the rack section.

I have herein shown and described what I now consider the preferred manner of carrying out my invention, but the same is merely illustrative and I contemplate all changes and modifications that come within the scope of the claims 40 appended hereto.

I claim:

1. In hinge means for a removable section of a floor rack for a refrigerator car having a side wall and a bottom wall, the combination 45 50 with a hinge keeper member fixed to the car, said keeper having a lengthwise extending guideway provided with a retaining guide wall, said retaining wall being cut away to provide an entrance opening to said guideway; of a hinge arm rigidly fixed to said rack and having a pivot pin 55 60 trunnion element slidably and rotatably engaged within said guideway in back of said retaining wall of said keeper member; and means fixed with respect to said hinge arm having bearing engagement with one of said walls of the car during swinging movement of said rack section to slide said pivot pin element along said guideway to bring said element in alignment with the 65 70 cut away portion of said retaining wall to permit detachment of said rack by withdrawal of said pivot pin element from said guideway through said cut away portion in said retaining wall.

2. In hinge means for a removable section of a floor rack for a refrigerator car having a side wall and a bottom wall, the combination with a keeper member fixed to one of said walls of the car, said keeper member being provided with a longitudinally extending guideway having an 75 overhanging retaining wall, a portion of which

is cut away; of a fixed arm on said rack section, said arm having a hinge pin member rigid therewith, said pin being anchored to said keeper member in back of said retaining wall for sliding and pivotal movement in said guideway to support the rack section for swinging movement from one of said car walls toward the other, said arm having riding sliding engagement with one of said walls of the car during said swinging movement of the rack to effect sliding movement of said hinge pin member along said guideway to bring said pin member into alignment with the cut away portion of said retaining wall to permit removal of said pin from the guideway and detachment of said rack section. 10 15 20

3. In hinge means for a removable section of a floor rack for a refrigerator car having a horizontal bottom wall and a vertical side wall, the combination with a keeper member fixed to one of said walls of the car, said keeper having a longitudinal guideway and side ledges overhanging said guideway; of a fixed arm on said rack section, said arm extending through the space between said ledges and having a pivot pin rigid therewith engaged in back of said ledges for sliding and pivotal movement, said arm having an extended portion engageable with the other of said walls of the car to ride on said wall to force the pivot pin to travel along said guideway while said rack section is being swung about the pivotal 25 30 axis of said pivot pin.

4. In hinge means for a removable section of a floor rack for a refrigerator car having bottom and side walls, the combination with a keeper member fixed to one of said walls of the car, said 35 keeper member including a plate provided with a longitudinal slot, a portion of said slot being laterally enlarged; of a fixed arm on said rack section, said arm extending through the slot of said plate and having a rigid pivot pin member 40 45 thereon of greater length than the width of said slot and engaged in back of the plate, the length of said pivot member being less than the width of said enlarged portion of the slot, said arm having a section thereof engaged with the other of said 50 walls of the car during pivotal movement of the rack with said hinge member, to effect sliding movement of the pivot pin along said slot to bring the pin into alignment with said laterally enlarged portion of said slot. 55

5. In hinge means for a removable section of a floor rack for a refrigerator car having side and bottom walls, the combination with a keeper member fixed to the car, said keeper member including a longitudinally slotted plate, the slot of 55 said plate being widened near one end thereof; of a rigid arm on said rack section, said arm having a fixed transverse pivot pin at the outer end thereof extending from opposite sides of said arm, said pivot pin being of a length greater than 60 the width of said slot and less than the width of said widened portion of the slot, said arm extending through the slot with the pivot pin thereof engaged in back of the walls of said plate adjacent said slot, said arm having a lever section engageable with one of said walls of the car to effect sliding movement of the hinge pin along the slot of said plate. 65

6. In hinge means for a removable section of a floor rack for a refrigerator car having a horizontal bottom wall and a vertical side wall, the combination with a keeper plate fixed to one of said walls, said plate having a longitudinal slot therethrough widened at one end; of a rigid hinge bracket on said rack, said bracket having a rigid 70 75 80 85 90 95

transverse pivot pin thereon projecting at opposite sides of said bracket, said pin being of a size to freely enter said widened portion of the slot and extend beyond opposite sides of the narrower portion thereof, said pin being engaged in back of said plate, said bracket including an arm engageable with the other of said walls to control sliding movement of the hinge pin lengthwise of said plate as said rack section is swung on said pivot pin.

7. In hinge means for a floor rack member of a refrigerator car having a side wall and a floor, the combination with a keeper fixed to the floor of the car, said keeper having a longitudinal, horizontal guideway, and a longitudinal slot of lesser width than said guideway communicating with the latter, said slot being widened laterally at one end; of an arm fixed to the rack member, said arm riding on said side wall and having a fixed transverse pivot pin at the free end thereof of a size to freely pass through said widened portion of the slot, said pin being of greater length than the width of the narrower portion of said slot, said arm being anchored to the keeper by the pivot pin thereof being engaged within said guideway with the arm extending through said slot.

8. In hinge means for a floor rack member of a refrigerator car having a side wall and a floor, the combination with a keeper fixed to the floor, said keeper including a horizontal guide plate having a longitudinally disposed slot extending therethrough, said slot being laterally enlarged at one end; of a rigid lever arm on said rack member engageable with said side wall and having a fixed transverse pivot pin at one end, said pin being of a size to freely enter said enlarged portion of the slot and extend beyond opposite sides of said slot, said arm extending through said slot with the pivot pin thereof engaged with the back of said plate at opposite sides of said slot.

9. In a hinge means for a floor rack member of a refrigerator car having a side wall and a floor, the combination with a keeper fixed to the floor at said side wall, said keeper having a guideway provided with overhanging retaining ledges extending lengthwise thereof and defining a slot therebetween, said slot being widened at one end; of a vertical hinge arm rigid with said rack member adapted to ride on said side wall and having a fixed pivot pin at its free end engaged within said guideway of the keeper with the arm extending through said slot, said pivot pin projecting from opposite sides of said arm, the lateral projection of said pin at opposite sides of said arm being within the limits of said widened portion of said slot and beyond the limits of the narrower portion thereof.

10. In a hinge means for a floor rack member of a refrigerator car having a side wall and a floor, the combination with a keeper fixed to the car floor at said side wall, said keeper including a longitudinally disposed, horizontal plate having a longitudinal slot, and a longitudinal guideway beneath said plate with which the slot communicates, said slot being widened at the end thereof remote from said side wall; of a bracket rigid with said floor rack member, said bracket including a fixed arm, said arm extending through the slot of said keeper and into the guideway thereof, said arm having laterally extended pivot projections on opposite sides of the free end thereof engaged within said guideway to anchor said rack member for swinging movement, said pivot projections extending laterally beyond the limits of said slot, the lateral projection of said pivot pro-

jections being less than the width of said widened portion of the slot; and means on said bracket for closing said slot and its widened portion when the rack member is in position overlying the floor of the car.

11. In a hinge means for a floor rack member of a refrigerator car having a side wall and a floor, the combination with a keeper plate fixed to the floor, said keeper plate having a longitudinally extending slot therethrough, said slot being widened at one end; of a hinge bracket on said rack member rigid therewith; a pivot pin member rigid with said bracket and pivotally and slidably connecting said hinge bracket and rack member to the plate, said bracket passing through the slot of said plate with the pivot pin member in shouldered engagement with the back of said plate, said pivot pin connecting the rack member to the floor of the car for swinging movement to permit the rack member to overlie the floor or stand in upright position against the side wall of the car; and means on said bracket closing said slot when the rack member is in overlying relation with respect to said floor.

12. In a hinge means for a floor rack member of a refrigerator car having a side wall and a floor, the combination with a keeper plate fixed to the floor, said keeper plate having a longitudinally extending slot therethrough, said slot being widened at one end; of a hinge bracket on said rack member rigid therewith; a pivot pin member rigid with said bracket and pivotally and slidably connecting said hinge bracket and rack member to the plate, said bracket passing through the slot of said plate with the pivot pin member in shouldered engagement with the back of said plate, said pivot pin connecting the rack member to the floor of the car for swinging movement to permit the rack member to overlie the floor or stand in upright position against the side wall of the car; and means on said bracket closing said slot when the rack member is standing in said upright position.

13. In hinge means for a floor rack of a refrigerator car having a side wall and a floor, the combination with a horizontally disposed slotted keeper plate fixed to the floor, said plate being longitudinally slotted; of a hinge bracket rigid with said rack member, said bracket extending through and being movable in said slot; pivot means rigid with said bracket and anchored beneath said plate for rocking sliding movement to permit said rack member to be positioned to overlie said floor or stand in upright position against the side wall of the car; and means on said bracket for closing said slot when the rack is in either of said positions.

14. In hinge means for a floor rack of a refrigerator car having a side wall and a floor, the combination with a horizontally disposed, longitudinally slotted keeper plate fixed to the floor; of a hinge bracket on said rack, rigid therewith, said bracket including an arm having a pivot means rigid therewith and engaged beneath said plate with the arm working in said slot, said pivot guiding the rack for swinging movement to permit the same to be brought either to horizontal position overlying the floor or vertical upright position against the side wall of the car, said arm being brought into position to occupy said slot when the rack member is in horizontal position, said arm being of a size to completely close said slot when the rack is in said horizontal position.

15. In hinge means for a floor rack of a re-

frigerator car having a side wall and a floor, the combination with a hinge bracket on said rack member; of a keeper; and pivot means on said bracket for swingingly connecting the rack member to the keeper to permit swinging of the rack to horizontal position overlying the floor and to vertical upright position against the side wall of the car, said bracket having a pair of arms rigid therewith, said arms extending at right angles to each other and being connected at their outer ends and having the pivot means of the bracket at said connection, said keeper including a horizontally disposed anchoring plate, said plate having a longitudinal slot adapted to accommodate either of said arms for movement therein, said pivot means being engaged beneath the plate, and said arms being respectively brought into position to occupy said slot from end to end when the rack member is respectively in horizontal and upright positions, each of said arms being of a size to seal said slot when occupying the same.

16. In hinge means for a floor rack member of a refrigerator car having a side wall and a floor, the combination with a keeper fixed to said wall, said keeper having a longitudinally disposed vertical guideway; of an arm projecting from and rigid with said rack member; pivot means on said arm slidably guided in said guideway; and a rocker on said arm, rigid therewith, for supporting said rack member in its swinging movements.

17. In hinge means for a floor rack member of a refrigerator car having a side wall and a floor, the combination with a keeper fixed to said wall, said keeper having a longitudinally disposed

guideway, said guideway being closed by a longitudinally slotted keeper plate, the slot of which communicates with said guideway, said slot being laterally enlarged near its lower end, the narrower portion of said slot being narrower than the guideway; of an arm rigid with said rack member, said arm having a pivot pin working in said guideway, said pin being of lesser length than the width of said widened portion of said slot and of greater length than the width of the narrower portion of said slot, said arm having a flat supporting portion adapted to support the rack in position with the pivot pin of said arm aligned with the widened portion of the slot of the keeper plate.

18. In hinge means for a floor rack member of a refrigerator car having a side wall and a floor, the combination with a keeper fixed to said wall, said keeper having a longitudinally disposed guideway, said guideway being closed by a longitudinally slotted keeper plate, the slot of which communicates with said guideway, said slot being laterally enlarged near its lower end, the narrower portion of said slot being narrower than the guideway; of an arm rigid with said rack member, said arm having a pivot pin working in said guideway, said pin being of lesser length than the width of said widened portion of said slot and of greater length than the width of the narrower portion of said slot, said arm having a rounded projecting bearing portion adapted to support said rack member for rocking movement and maintain said pin engaged in said guideway.

STACY B. HASELTINE.
